US00D874712S

(12) **United States Design Patent** (10) **Patent No.:** **US D874,712 S**
(45) **Date of Patent:** **** Feb. 4, 2020**

(54) **STRUCTURAL FRAME**

(71) Applicant: **Brian M. Adams**, Bellbrook, OH (US)

(72) Inventor: **Brian M. Adams**, Bellbrook, OH (US)

(**) Term: **15 Years**

(21) Appl. No.: **29/636,129**

(22) Filed: **Feb. 6, 2018**

(51) **LOC (12) Cl.** **26-03**

(52) **U.S. Cl.**

USPC **D26/118; D6/708**

(58) **Field of Classification Search**

USPC D6/708, 708.1, 708.11–708.23; D26/1, D26/24, 67, 93–95, 101, 104–110, 112, D26/118, 120, 121, 128, 129

CPC .. F21Y 2103/00; F21Y 2101/02; F21V 15/00;

F21V 25/00
